CLAIM

The ornamental design for a lighted bicycle wheel, as shown and described.

DESCRIPTION

FIG. 1 is a front, top and side perspective view of the lighted bicycle wheel showing my new design;

FIG. 2 is a front elevational view thereof, the rear being a mirror image of the front shown in FIG. 2; and,

FIG. 3 is a side elevational view thereof, the side opposite, the top and bottom all being mirror images of the side shown in FIG. 3.

FIG. 1

FIG. 2

FIG. 3
